UNITED STATES PATENT OFFICE.

JAMES M. CONNER, OF GREENVILLE, NEW JERSEY.

DESIGN FOR FONT OF PRINTING-TYPES.

Specification forming part of Design No. **11,128**, dated April 1, 1879; application filed February 26, 1879.
[Term of patent 7 years.]

To all whom it may concern:

Be it known that I, JAMES M. CONNER, of Greenville, Hudson county, New Jersey, have invented and produced a new Design for a Font of Printing-Types, of which the following is a specification:

The nature of my design is clearly shown in the accompanying typographic impression, to which reference is made; and consists of an ornamental letter shaded upon the right and bottom by a heavy line, followed by a lighter one.

The up-and-down portions of all the letters are composed of two curvilinear triangles, united at the apices by an elliptical ring.

The faces of the letters are ornamented by shaded spaces, the outlines of which are parallel to the outlines of the parts of the letters where they are placed.

In the letters A and T the lower triangles are continued, so as to form the triangular or spur projections, which extend upward.

In the letters B, D, E, F, H, I, K, L, M, N, P, R, X, and Y, both triangles have triangular projections.

In the letter G the lower curved portion is ornamented by a similar triangular or spur projection and the elliptical ring.

The letters J, U, V, and W have the upper triangles continued to form the triangular or spur projections.

In A and H a rhomboidal ornament connects the rings.

In B and R the ring is succeeded by a rhomboidal ornament.

In the symbols & \$ £ the character of the design is preserved, the ornamental triangular projection occurring in the symbol & at the bottom and on the right.

The figure 1 is like the letter I, with the exception of the omission of the right-hand triangular projection on the upper triangle.

The character of the design is preserved in the figures 2 3 4 5 6 7 8 9 0 and in the lower-case of the font, the triangular projections occurring in the letters a, b, f, h, i, j, k, l, m, n, p, q, r, t, u, v, w, x, and y.

Having now described my invention, what I claim as new is—

The design for a font of printing-types, as shown and described.

JAMES M. CONNER.

In presence of—

Wm. C. CONNER, Jr.,
THOS. G. WILSON.
